UNITED STATES PATENT OFFICE

100,990

DESIGN FOR A RADIANT FOR HEATERS

Robert C. Deigert, Toledo, Ohio, assignor to Utility Gas Appliance Corporation, Columbus, Ohio, a corporation of Ohio

Application March 30, 1936, Serial No. 61,860

Term of patent 7 years

To all whom it may concern:

Be it known that I, Robert C. Deigert, a citizen of the United States, and resident of Toledo, county of Lucas, State of Ohio, have invented a new, original, and ornamental Design for a Radiant for Heaters, of which the following is a specification, reference being had to the accompanying drawing, forming a part thereof.

Fig. 1 is a front elevational view of a radiant embodying my new design; Fig. 2 is a side view thereof, and Fig. 3 is a bottom plan view.

The dominant feature of the invention resides in the vertical continuous central members, which extend from the base to the curved top;

the cross members which intersect the inner vertical members and present therewith a somewhat cruciform appearance, and the ribs at the rear which at their lower ends are spaced above the lower ends of the vertical members and at their upper ends are spaced below the tops of said latter members.

I claim:

The ornamental design for a radiant for heaters, substantially as shown and described.

In testimony whereof I have hereunto signed my name to this specification.

ROBERT C. DEIGERT.
